CLAIM

The ornamental design for a ammunition carrier tube, as shown and described.

DESCRIPTION

FIG. 1 is a front perspective view of a ammunition carrier tube showing my new design and further showing in dotted line, for illustrational purposes only, the manner in which the carrier is attached to adjacent carriers;

FIG. 2 is a front perspective view of a ammunition carrier tube showing my new design;

FIG. 3 is a left side view thereof, of which view taken from the top, bottom, right side would be the same;

FIG. 4 is a front elevational view thereof;

FIG. 5 is a rear elevational view thereof; and,

FIG. 6 is a cross sectional view thereof taken along line 3—3 of FIG. 4.

1 Claim, 4 Drawing Sheets

FIG. 1

FIG. 2
